UNITED STATES PATENT OFFICE.

HARRY NEVILLE, OF LOS ANGELES, CALIFORNIA, ASSIGNOR OF ONE-FIFTH TO GEORGE H. GOODWIN, ONE-FIFTH TO DANIEL P. KELLOGG, ONE-FIFTH TO WILLIAM F. MERRY, AND ONE-FIFTH TO PATRICK SHEEDY, ALL OF LOS ANGELES, CALIFORNIA.

SAFETY APPARATUS FOR STEAM-BOILERS.

1,004,896.

Specification of Letters Patent.

Patented Oct. 3, 1911.

Application filed June 2, 1910. Serial No. 564,616.

To all whom it may concern:

Be it known that I, HARRY NEVILLE, a citizen of the United States, residing at Los Angeles, in the county of Los Angeles and 5 State of California, have invented certain new and useful Improvements in Safety Apparatus for Steam-Boilers; and I do declare the following to be a full, clear, and exact description of the invention, such as 10 will enable others skilled in the art to which it appertains to make and use the same.

This invention relates to safety devices for steam boilers by the use of which explosions are prevented and the primary object 15 of the invention is to provide a device which will be located entirely exteriorly to the boiler and will have a single point of communication therewith whereby certainty 20 in the operation of the apparatus will be assured.

A further object of the invention is to provide means whereby, when the water of the boiler reaches a predetermined level, 25 an alarm will be automatically sounded and on the continuance of the abnormal condition the fire will be automatically extinguished.

With these and other objects in view, the 30 invention consists of certain novel features of construction, combination and arrangement of parts as will be more fully described and particularly pointed out in the appended claims.

35 In the accompanying drawings: Figure 1 is a front end view of an oil burning boiler showing the invention applied thereto. Fig. 2 is a side view of the same. Fig. 3 is a front view of a coal or wood burning 40 boiler showing the invention applied thereto. Fig. 4 is a side view partly in section of the boiler shown in Fig. 3. Fig. 5 is an enlarged vertical sectional view of the valve and the means whereby the same is automatically 45 opened to admit steam to the alarm and to the fire controlling devices. Fig. 6 is a detail section of the ring which supports the locking pin for the packing nut on the valve. Fig. 7 is a horizontal sectional view on the line 7—7 of Fig. 5. Fig. 50 8 is a similar view on the line 8—8 of Fig. 5. Fig. 9 is a longitudinal sectional view of the oil fuel controlling valve and means for operating the same. Fig. 10 is a cross sec-

tional view of the valve shown in Fig. 9 and taken on the line 14—14 of said figure. Fig. 11 is a longitudinal sectional view of the valve for controlling the water for putting out a wood or coal fire. Fig. 12 is a cross sectional view on the line 16—16 of Fig. 11. Fig. 13 is a similar view of the valve for cutting off steam from the alarm, indicator and inspirator operating valve.

Referring more particularly to the drawings 1 denotes a boiler to which is applied and secured at any desired position my improved safety mechanism, said mechanism comprising a steam and water cylinder 2 having on one side apertured ears or lugs 3 whereby the same is bolted or otherwise secured to the boiler as shown. On the opposite side of the cylinder 2 is formed a wing or extension 4 through which is formed a series of transverse tubes 5 which permit a circulation of air which serves to cool the cylinder.

In the wing or extension 4 adjacent its upper end is formed a threaded port 6 while at its lower end is formed a threaded port 7, said ports being connected by a longitudinal passage 8. With the ports 6 and 7 are connected steam and water conducting tubes 9 and 10 which are joined adjacent the cylinder 2, as shown, and lead to a valve 11 which in turn is connected with a nipple 12 arranged in the boiler at such a point as has been determined upon as a low water level or danger point. By thus arranging the nipple 12 and connecting pipes 9 and 10 water from the boiler will enter the cylinder 2 as long as the level of said water remains above the nipple, the level of the water in the cylinder and the boiler being the same. As the water in the boiler falls below the level of the nipple the water will run out of the cylinder 2 back into the boiler and will be replaced by steam passing through the nipple from the boiler which will operate the mechanism in the manner hereinafter described.

In the lower end of the cylinder 2 is formed a threaded blow off port 13 with which is connected a blow off pipe 14 having arranged therein a cut off valve 15. By means of the blow off port 13 and pipe 14 any sediment or corrosion may be blown out of the cylinder and the latter thus kept clean and free from foreign matter. In

the upper end of the cylinder 2 is formed a threaded opening in which is screwed a cap nut 16 having an interiorly and exteriorly threaded inner end. Into the interiorly threaded inner portion of the cap nut is screwed the upper flanged end of a mercury cup 17 in the lower end of which is screwed a plug 18. The cup 17 is adapted to contain mercury which is expanded by the action of steam in the cylinder and thereby operates the alarm mechanism hereinafter described.

In the cap nut 16, immediately above the flanged upper end of the mercury cup, is arranged a steel diaphragm 19 the outer edge of which is clamped between suitable packing washers or rings 20 arranged and clamped between the flanged upper end of the mercury cylinder and the adjacent portion of the cap nut 16 as shown. With the diaphragm 19 is engaged the headed lower end of a valve lifting pin 21 which has a sliding engagement with a stuffing box 22 arranged in the upper portion of the cap nut 16 as shown. On the upper side of the cap nut 16 is formed an interiorly threaded socket 23 into which is screwed the lower end of a valve casing 24 within which is arranged a valve seat 25 adapted to be engaged by a valve 26. The valve 26 is provided with a tubular downwardly projecting stem 27 the lower end of which has a sliding engagement with a stuffing box 28 arranged in an enlarged hollow portion 29 of the valve casing 24 as shown. In the sides of the enlarged portion 29 of the valve casing is formed a series of radial openings 30 which permit a circulation of air for the purpose of cooling the device and which also provide means whereby access may be had to the packing nut of the stuffing box 28.

The head of the packing nut is provided with an annular series of notches 31 adapted to be engaged by a locking pin 32 slidably mounted in a socket 33 formed on a supporting ring 34 which engages the valve casing 24 and rests upon the enlarged portion 29 thereof as shown. The ring 34 is formed in two sections, the ends of which are riveted together after being engaged with the valve casing thereby securely holding said ring and the socket 33 in place. The locking finger 32 is provided with a reduced stem 35 which projects through a guide opening in the end of the socket and is provided with a removable head 36. On the reduced stem 35 of the locking pin in the socket 33 is arranged a coiled spring 37 the pressure of which is exerted to force the pin inwardly and into engagement with the notches 31 in the nut 28 thereby holding said nut against retrograde movement after it has been adjusted to the desired extent.

On the upper end of the valve 26 is formed a tubular exteriorly threaded extension 38.

The lower end of the tubular valve stem 27 is interiorly threaded, as shown at 39, and with said interiorly threaded portion 39 is engaged the threaded lower end of a pressure regulating rod or bolt 40 which extends upwardly through the tubular valve stem. The extension 38 on the upper end of the valve passes through a stuffing box 41 arranged on the threaded extension 38. The upper end of the rod or bolt 40 is threaded and projects above the stuffing box 41 and has fitted thereon a lock nut 42. On the extreme upper end of the rod or bolt 40 is formed a squared wrench receiving extension 43 whereby said bolt may be screwed up or down in the tubular stem 27 of the valve 26 thereby regulating the position of the lifting pin 21 which engages the diaphragm 19 and has its upper end projecting a slight distance up into the valve stem 27 as shown. After the bolt or rod 40 has thus been adjusted the lock nut 42 is screwed down on the threaded upper end of the bolt and into engagement with the stuffing box 41 thereby locking the bolt in its adjusted position.

Adapted to be screwed into the upper end of the valve casing 24 is a protecting cap 44 which covers the upper end of the bolt 40 and the adjusting nut 42 and stuffing box 41 thus preventing tampering with or injury to these parts. Arranged in the cap 44 and bearing upon the lock nut 42 is a coiled spring 45 the pressure of which is exerted to hold the valve 26 in yielding engagement with its seat 25 in the valve casing 24. On the lower end of the lifting pin 21 between the head thereof and the inner wall of a recess 46 formed in the cap nut 16 is a coiled pin projecting spring 47 the pressure of which is exerted to force the lifting pin 21 and the diaphragm 19 downwardly into an operative position for engagement by the mercury when the same is expanded in the cup 17.

As the cylinder 2 is on the outer side of the boiler, the water in the same will naturally be of a lower temperature than the water within the boiler and the temperature of the water in the cylinder 2 will not be sufficient to cause the mercury in the cup 17 to expand. When, however, the water in the boiler falls below the level of the nipple 12, the water in the cylinder 2 will run back in the boiler and the steam will enter the cylinder 2, the temperature of this steam causing the mercury in the cup 17 to expand against the diaphragm 19 the lifting pin 21 will be raised and by reason of its engagement with the lower end of the bolt 40 will raise said bolt and the valve 26 against the pressure of the springs 45 and 47, thus allowing steam or other fluid to pass through the valve casing 24 for the purpose of sounding an alarm. This alarm will notify the attendant of the low level of the

water in the boiler, but to increase the efficiency of the apparatus in preventing explosions, I preferably provide means to automatically extinguish the fire or to restore 5 the water level should the attendant not respond promptly to the alarm.

One end of the valve casing 24 is connected by a steam supply pipe 48 with the usual steam distributing chest or dome 49 arranged 10 on and connected with the boiler. The pipe 48 is provided with a cut off valve 50 whereby the flow of steam to the valve casing 24 is controlled. While I have shown and described the pipe 48 as being connected with 15 a steam distributing chest it is obvious that said pipe may be connected directly to the boiler or to any live steam pipe leading therefrom. The opposite end of the valve casing 24 has connected thereto a nipple 20 51 with which is engaged a fourway coupling 52 to one branch of which is connected a steam conducting pipe 53 which in Figs. 1 and 2 of the drawings is shown as extending laterally and downwardly below the 25 boiler where it is connected with the cylinder 54 of an automatically operated fuel controlling valve 55 for cutting off the supply of oil fuel from the burners 56 of the boiler. The steam cylinder 54 has arranged 30 therein a piston 57 the piston rod 58 of which is connected to the valve 55 which is slidably mounted in the valve casing 59 to which is connected the oil supply pipe for the burners 56. In the cylinder 54 and engaging the piston 57 is a valve opening spring 60. The steam conducting pipe 53 is connected with the head of the cylinder 54 whereby the steam entering said cylinder from said pipe will force the piston forwardly against the pressure of the spring 60 thereby closing the valve 55 and holding the same in closed position as long as the steam pressure is maintained in the cylinder. When the cylinder is relieved from said 45 steam pressure the spring 60 will retract the piston thereby opening the valve 55 and permitting the oil to again flow to the burners. The piston rod 58 works through a stuffing box 61 whereby oil which may possibly get past the valve 55 is prevented from 50 entering the steam cylinder. In the head of the cylinder is formed a port 62 to permit the discharge of condensed steam and in said cylinder on the opposite side of the piston is also formed a port 63 whereby any water which may have leaked past the piston is permitted to drain from the casing. It will be understood, of course, that the oil supply is admitted to the valve casing 59 55 through a main supply pipe fitted with a hand valve. When the valve 55 cuts off the flow to the burners, this hand valve is closed and remains closed until after normal conditions are restored in the boiler. It is then 60 again opened and the oil again ignited un-

der the boilers in the same manner as when starting the apparatus in the first instance.

In Figs. 3 and 4 of the drawings is shown a steam conducting pipe 53^a which is connected with the fourway coupling 52 70 and takes the place of the steam conducting pipe 53 shown in Figs. 1 and 2 of the drawings. The pipe 53^a is employed in connection with wood or coal burning boilers and extends downwardly and inwardly 75 to a position immediately above the fire in the fire box of the boiler. The lower end of the pipe 53^a is connected with the steam cylinder 64 containing mechanism through which water is let into the fire box for the purpose of quenching the fire. With one end of the cylinder 64 is connected a valve casing 65 in which is arranged a cut off valve 66 with one end of which is connected a water conducting pipe 67 and with the opposite end of which is connected a water supply pipe 68 having arranged therein a controlling valve 69. The pipe 67 is connected with a series of hollow stay bolts 70 arranged between the outer shell of the 90 boiler and the fire box and through which the water is injected or sprayed onto the fire thus extinguishing the same.

The valve 66 in the casing 65 is connected to one end of a piston rod 71, the 95 opposite end of which projects through a stuffing box 72 and into the steam cylinder 64 and is connected with a piston 73 which works in said cylinder. Between the piston 73 and the head of the cylinder is arranged 100 a coiled spring 74 the pressure of which is exerted upon the piston to cause the latter to close the valve 66 and to normally hold the same in closed position thus cutting off the water from the pipe 67 until the valve 105 is opened by the pressure of steam admitted to the steam cylinder 64 through a steam port 75 arranged in one side of the cylinder between the piston and the adjacent end of the cylinder as clearly shown in Fig. 15 110 of the drawings. The cylinder 64 is provided with drain ports corresponding to the drain ports in the cylinder 54 for the purpose of discharging the waters of condensation from said cylinder.

With the fourway coupling 52 is also connected a steam conducting pipe 76 which extends to a coupling 77 with which is connected a steam conducting pipe 78 leading to a whistle 79 which is operated by the 120 steam passing through said pipes to sound an alarm which will give notice that the water in the boiler has reached the danger level. With the coupling 77 is also connected a steam conducting pipe 80 which 125 extends around one side of the boiler and is connected with a steam cylinder 81 containing a piston on the projecting end of which is a clevis 84 adapted to engage the operating lever of an inspirator, whereby 130

water is supplied to the boiler. With the coupling 77 is also connected a steam conducting pipe 87 which leads to and is connected with a recording indicator 88 by means of which the number of times the water in the boiler has reached a low water level will be indicated and recorded.

Should the pressure of the steam increase notwithstanding its use to operate the whistle, the indicator, and the inspirator in the described manner, the entire force of the steam is thrown onto the controlling devices at the fire line. The means for thus cutting off the whistle, inspirator and indicator comprises a cylinder 105 which is connected at one end by a pipe 106 to the four-way coupling 52. The cylinder 105 has arranged therein a spring retracted piston 107, the piston rod 108 of which works through a stuffing box and projects into a valve casing 109 arranged in the steam conducting pipe 76. On the projecting end of the piston rod 108 is arranged a valve 110 which is operated by the movement of the piston to cut off the supply of steam passing through the pipe 76 to the whistle indicator and inspirator operating mechanism. By means of the steam cylinder 105 and the valve operating mechanism arranged in and connected therewith the steam after reaching a pressure sufficient to overcome the spring in the cylinder, will close the valve 110 in the manner and for the purpose described.

The ordinary operation of the device will seat the valve 26 just after the inspirator is actuated, but should the steam be generated so rapidly as to approach the danger point and prevent such action, the steam will pass to the cylinder 54 or 64, as the case may be, and exert a pressure on the piston therein sufficient to overcome the resistance of the spring bearing on the piston so that the fire will be extinguished in the hereinbefore described manner.

When the valve 26 is opened, steam will flow to the coupling 52 and the main portion thereof will follow the straight path defined by the pipe 76 and will, consequently, pass to the whistle, the indicator, and the inspirator. Some of the steam will, however, pass through the pipe 106 to the cylinder 105 and some will also pass to the combustion controlling devices, but the spring in the cylinder containing the combustion controlling devices and the spring in the cylinder 105 will be strong enough to withstand the initial pressure of the steam and hold the pistons in their respective normal or initial positions until steam accumulates in the respective pipes in sufficient quantities to exert a pressure which will overcome the resistance of the said springs. The cut-off is thus gradually projected across the pipe 76 so that the steam will be prevented from flowing to the whistle, the indicator, and the

inspirator, and the entire body of steam will then be directed to the combustion controlling devices so that the valves will be operated to extinguish the fire or cut off the supply of fuel as heretofore described. The attendant will thus have time enough to restore normal conditions in the boiler before the fires will be automatically extinguished, but, if such attention should not be given, the full pressure of the steam will be exerted upon the combustion controlling devices to operate the same.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention as defined in the appended claims.

Having thus described my invention, what I claim is:

1. The combination with a steam boiler, of an alarm, a pipe leading from the steam space in the boiler to the alarm, a valve in said pipe, a coupling in said pipe beyond said valve, a cut-off beyond the said coupling disposed normally at one side of said pipe, a pipe leading from said coupling to said cut-off to admit steam thereto whereby to project it across the first-mentioned pipe, a pipe leading from said coupling to the fire box of the boiler, a valve arranged adjacent the fire box to be actuated by the steam passing through said pipe to control the combustion, a steam casing on the boiler and communicating therewith, and a heat responsive element in said casing to operate first-mentioned valve.

2. The combination with a steam boiler, of an alarm, a pipe leading from the steam space of the boiler to the alarm, a valve within said pipe, a coupling in said pipe beyond said valve; a pipe leading from said coupling to the fire box of the boiler, combustion controlling devices adjacent the fire box and actuated by the steam passing through said pipe, a cylinder beyond the coupling at one side of the pipe leading from the steam space of the boiler, a piston within said cylinder carrying a cut-off adapted to project across the first-mentioned pipe, a spring within the cylinder to hold the piston normally elevated, a pipe carrying steam from the coupling to the said cylinder, a steam casing on the boiler communicating therewith, and a heat-responsive element in said casing to open the valve and admit steam to the cylinder whereby the piston will be lowered and the cut-off projected across the pipe leading from the steam space of the boiler.

3. The combination with a steam boiler, of an alarm connected therewith, combustion-controlling devices, heat-responsive mechanism connected with the boiler and arranged to admit steam to the alarm, and connections between the alarm and the combustion-controlling devices whereby prolonged admission of steam by the heat-responsive mechanism will stop the alarm and

cause the combustion-controlling devices to 10 arrest combustion.

In testimony whereof I have hereunto set my hand in presence of two subscribing witnesses.

HARRY NEVILLE.
